his Atty.

UNITED STATES PATENT OFFICE.

CHARLES MORE HUNT, OF IRENA, MISSOURI.

FLOOD OR WATER GATE.

SPECIFICATION forming part of Letters Patent No. 427,084, dated May 6, 1890.

Application filed February 27, 1890. Serial No. 341,915. (No model.)

To all whom it may concern:

Be it known that I, CHARLES MORE HUNT, a citizen of the United States, residing at Irena, in the county of Worth and State of Missouri, have invented certain new and useful Improvements in Flood or Water Gates; and I do declare the following to be a full, clear, and exact description of the invention, such as will enable others skilled in the art to 10 which it appertains to make and use the same, reference being had to the accompanying drawing, and to the letters of reference marked thereon, which forms a part of this specification.

15 My invention relates to flood or water gates for continuing a line of fence across a water-course; and it consists of a novel method of constructing and hanging the same, so that there will be no sagging, and also so as to permit 20 its lower end to swing out on the surface of the water when it rises to any unusual height.

The drawing represents the construction of my gate and the method of hanging it.

25 A A are the supporting-posts on the banks through which the stream runs and between which the gate is hung.

30 B B B are upright pieces equidistant from each other, to which are securely attached on their lower ends cross-pieces C C C, also equidistant, as shown. There may be more uprights and more cross-pieces than are shown to suit the width and depth of the stream for which the gate is required. In the same vertical plane with the upright pieces shorter pieces 35 or bars D D are connected to the posts A A by bolts E E, so as to turn freely on the bolts. The outer ends of the bolts are provided with screw-threads and nuts, as shown. The upper ends of the pieces D D are nearly in line 40 with the upper ends of the uprights.

a, b, and c are wire braces connecting the uprights B to the pivoted pieces or bars D D, arranged as shown. The wires *b*, three in number, pass through the upper ends of the uprights B parallel with the cross-pieces C. 45 The upper and lower connect with the ends of the bars D, forming cross-braces. The middle wire *b* connects at the outer edge of the outer uprights B with wires *a*, that run to the connecting ends of the upper and lower wires 50 *b* and connect there with the pieces D D, as shown, forming diagonal braces. The wires *c* extend from the same connecting-point near the lower ends of the pieces D D to near the lower end of the middle upright B, as shown, 55 also forming diagonal braces.

The uprights B, cross-pieces C, pivoted pieces or bars D, and wires *a, b*, and *c* form a gate, which is hung upon the bolts E. Washers may be placed upon these bolts between the 60 pieces D and the posts, if desired. The gate thus constructed will be rigid, and when hung will not sag, will swing freely on the water when it rises, and may be of any desired length.

Having thus described my invention, what 65 I claim is—

A flood or water gate consisting of the uprights B, cross-pieces C, pivoted pieces D, and wire braces *a, b*, and *c*, constructed substantially as described and hung upon bolts E, 70 as set forth.

In testimony whereof I affix my signature in presence of two witnesses.

CHARLES MORE HUNT.
